His Attorney.

UNITED STATES PATENT OFFICE.

ROBERT J. MULVEY, OF CHICAGO, ILLINOIS.

SNAP FASTENER.

1,405,933.

Specification of Letters Patent. Patented Feb. 7, 1922.

Application filed July 24, 1920. Serial No. 398,691.

To all whom it may concern:

Be it known that I, ROBERT J. MULVEY, a citizen of the United States, and a resident of the city of Chicago, county of Cook, and State of Illinois, have invented certain new and useful Improvements in Snap Fasteners, of which the following is a specification.

My invention relates to new and useful improvements in snap fasteners, and has for its object the improvement in construction, form and fastening means of the female member of the present day devices. Another object of the invention is the provision of such a device as to be simple in operation and economical of manufacture.

Other objects will appear hereinafter.

The invention consists in the combinations and arrangements of parts hereinafter described and claimed.

20 The invention will be best understood by reference to the accompanying drawings forming a part of this specification, and in which,

Fig. 1, is a plan view of the base of the 25 female member of the clasp,

Fig. 2, is a plan view of the upper side of the female member,

Figure 3, a cross sectional view taken on line 3—3 of Fig. 1,

30 Fig. 4, a sectional view of the clasp taken on line 4—4 of Fig. 3 and having a portion broken away,

Fig. 5, a cross sectional view taken on line 5—5 of Fig. 4, and

35 Fig. 6, a view of the fastening means fixed to a piece of fabric.

The preferred form of construction consists of a metallic disc 1 having its edges in-turned to form seats for the wire fastening means 2 and the locking means 3 and having a central depression forming a cup or socket 4, said cup being slotted as at 5 and 6 to accommodate the spring locking means 3. The locking means 3 consists of a torsionally bent wire spring which is seated upon the inner circumferential surface of the disc and having its opposite ends so bent as to allow them to seat within the slots 5 and 6 of the cup 4, the contour of said spring

45 causing its ends to be firmly seated in said slots. A metallic disc 7 having a central opening 8 encompasses the cup 4 and rests upon the locking means 3, holding it firmly in position. The inner edge of the metallic disc 1 is swaged under, forming a shoulder 9 and

separated from the locking means 3 by the plate 7 is an S-shaped wire fastening means, one end of which is seated within the shoulder of the clasp, the other end being bent in the shape of the letter S and having its extremity 10 bent so as to engage a loop 11 formed by a protrusion of the wire base from the shoulder 9. The operation of the fastening means is as follows:—The bent end 10 is released from engagement with the loop 11 and is forced through the piece of fabric to which it is to be attached. The clasp is then twisted clockwise about its circumference and the end 10 is again forced through the fabric and hooked under the loop 11, thus firmly securing the clasp to the fabric.

The clasp as a whole includes a male member and a female member. The male member, which forms the subject matter of another application, has a projecting stud having an enlarged head which fits into the cup-shaped socket 4 and is firmly held in position in said socket by means of the locking spring 80 3 firmly pressing against the neck of the stud.

While I have illustrated and described the preferred form of construction for carrying my invention into effect, this is capable 85 of variation and modification without departing from the spirit of the invention. I, therefore, do not wish to be limited to the precise details of construction set forth, but desire to avail myself of such variations and 90 modifications as come within the scope of the appended claims.

Having described my invention, what I claim as new and desire to secure by Letters Patent is:—

1. A device of the class described comprising a disc having a cup-shaped socket in the center thereof and an inturned outer edge forming a shoulder; fastening means held in position by said shoulder; locking means mounted upon the shoulder of said in-turned edge; and a metallic plate encompassing the socket and separating the locking means from the fastening means, substantially as described.

2. A device of the class described comprising a disc having a cup-shaped socket in the center thereof; slots in said socket; wire locking means having its opposite ends engaging said slots; a metallic plate encompassing said socket and firmly holding the locking means in position; and quick de-

tachable fastening means bearing against said plate and the shoulder formed by the in-turned edge of said disc, substantially as described.

5 3. A device of the class described comprising a disc having a cup-shaped socket in the center thereof; slots in said socket; locking means engaging said slots; a metallic plate encompassing said socket and bearing against said locking means; and fastening means held in position by means of the in-turned shoulder and the metallic plate,

said fastening means comprising an S-shaped wire one end of which is bent to engage a loop in the opposite end of said wire, 15 substantially as described.

In testimony whereof I have signed my name to this specification in the presence of two subscribing witnesses.

ROBERT J. MULVEY.
